UNITED STATES PATENT OFFICE.

PETER T. GRAVES, OF MILWAUKEE, WISCONSIN, ASSIGNOR TO THE MILWAUKEE CHAIR COMPANY, OF SAME PLACE.

DESIGN FOR A CHAIR.

SPECIFICATION forming part of Design No. 31,049, dated June 20, 1899.

Application filed May 11, 1899. Serial No. 716,444. Term of patent 7 years.

To all whom it may concern:

Be it known that I, PETER T. GRAVES, of Milwaukee, in the county of Milwaukee and State of Wisconsin, have invented and produced a new and original Design for Chairs, of which the following is a description, reference being had to the accompanying drawings, which are a part of this specification.

Figure 1 is a side elevation of a chair, showing my design. Fig. 2 is a perspective of the same chair at a slight angle to a square front view. Fig. 3 is a cross-section of an arm of the chair medially between the back and the front extremity of the arm.

The leading or material feature of the design is the shape and contour of the back and arms of the chair above the seat, in connection with the vertical spindles or rails between the back and the seat and in connection with and in relation to the seat of the chair. The back 5 of the chair has a substantially straight horizontally-disposed lower edge centrally and is of considerable width vertically, and the top edge of the back is curved upwardly centrally in contour, as seen from the front, and this upper curved edge or contour line continues downwardly at the respective ends of the back, running into the forwardly-extending surface-lines of the arms 30 of the chair. The arms of the chair are continued forwardly to the desired extent in a substantially horizontal plane, into which they are brought by curves from the back of the chair, and at the front extremity of such

forward extension of the arms they are turned 35 in curves abruptly downwardly and then rearwardly and downwardly, extending to the seat of the chair, against the side edges of which they bear and to which they are affixed near their extremities. The arms of 40 the chair have in cross-section a general parallelogram form, slightly varying in shape in different portions thereof and being slightly rounded at their corners and on their upper surfaces, as shown in the cross-section in Fig. 45 3. The back 5 is bowed from the central portion forwardly, the curve becoming more abrupt in the vicinity of the extremities of the back and near the vanishing of the back into the arms. The spindles or vertical rails 50 6 extend from the horizontally-disposed lower edge of the back 5 down to the rear portion of the seat 7, these spindles being curved forwardly and downwardly. The top edge of the back of the chair is also turned over rearwardly in a roll, as shown in Fig. 1, along the central portion thereof and laterally, diminishing toward and vanishing at the junction of the back with the arms. 55

What I claim as my invention is— 60

The design for a chair substantially as shown and described.

In testimony whereof I affix my signature in presence of two witnesses.

PETER T. GRAVES.
